UNITED STATES PATENT OFFICE.

EDWARD W. LEECH, JR., OF BALTIMORE, MARYLAND.

SPRING OILER.

Application filed March 29, 1922. Serial No. 547,619.

To all whom it may concern:

Be it known that I, EDWARD W. LEECH, Jr., a citizen of the United States, residing at Baltimore, in the State of Maryland, have invented certain new and useful Improvements in Spring Oilers; and I do hereby declare the following to be a full, clear, and exact description of the invention, such as will enable others skilled in the art to which it appertains to make and use the same.

My invention relates to spring oilers.

Among the objects of my invention are:

To provide an oiler which can be readily applied to the ordinary leaf springs employed in vehicles.

To provide an oiler which can be readily removed from the spring for the purpose of cleaning and the insertion of new oil dispensing material.

To provide an oiler which can be readily refilled without removal from the leaf spring.

These and other objects of my invention will be explained in the following specification, reference being had to the accompanying drawings, and the means by which said objects are effectuated will be definitely pointed out in the claims.

In the drawings:

Fig. 1 is a side view of a leaf spring equipped with a pair of my improved oilers.

Fig. 2 is an enlarged section along the line 2—2 in Fig. 1 looking in the direction of the arrows.

Fig. 3 is a detail view of one of the oiling members shown in Fig. 2.

Fig. 4 is a view of the parts shown in Fig. 2 looking in the direction of the arrow 4 in said figure, the spring 10 being omitted.

Fig. 5 is a section along the line 5—5 in Fig. 3 looking in the direction of the arrows, the distributing means for the oil being omitted.

Fig. 6 is a view of the member shown in Fig. 3 looking in the direction of the arrow 6 in said figure.

Fig. 7 is a partial view of the link 21 when viewed in the direction of the arrow 4 in Fig. 2.

Fig. 8 is a view of the link bar 26 when viewed in the direction of the arrow 4 in Fig. 2.

In the drawings:

10 is a spring having the usual plurality of leaves and 11 are oiling members of my improved oiler, one of which is applied to

each side of the spring and yieldingly held thereagainst as hereinafter explained. Each member 11 comprises a reservoir 12 for the oil 13 and the wick 14 is the means for distributing the oil from the reservoir 12 to the side of the spring 10.

The dust guards 15, formed of fabric or other compressible material, are mounted in grooves provided in the member 11 to shield the portion of the wick in contact with the spring 10 from dust. The top of the member 11 is provided with an interior thread at 16 and the cap 17 placed therein provides for ready access to the interior of the member 11 without removing the same from the spring 10. The reservoir 12 is provided with a screw hole closed by the screw 18 to provide means for introducing oil within the reservoir.

Near the top of the member 11 inclines 19—19 are provided which rest against inclines such as 20—20 provided on each end of the link 21. The link 21 is provided with a slot 22 for a purpose hereinafter explained.

The member 11 is provided at its lower end with a recess 23 having the inclined surface 24 against which rests the incline 25 formed on the end of the locking bar 26.

The spring 27 mounted between the locking bar 26 and the leaf spring 10 serves to press the inclines 25—25 against the inclines 24—24. The bar 26 is provided with a rib 28 extending around the same in order to prevent displacement of the spring 27.

The manner of use of my improved spring oiler is as follows:

The link 21 is to be placed upon the top of the spring 10 and the members 11 introduced within the slots 22. When the members 11 are introduced within the slots 22 the inclines 19 pass over the tops of the inclines 20. The bottoms of the members 11 are then to be moved outwardly sufficiently to allow the ends of the locking bar 26 to be placed within the recesses 23. The spring 27 is to be in place on the bar 26 when the ends of the latter are placed within said recesses.

The lower ends of the members 11 are then to be moved inwardly and when the bar 26 is released, the downward pressure of the spring 27 acting through the inclines 25 upon the inclines 24 will bring the lower ends of the members 11 inwardly until the wick 14 contacts with the sides of the leaf spring 10 and the downward pressure of the inclines 19 upon the inclines 20 will

also bring the upper ends of the members 11 inwardly.

When it is desired to remove the members 11 the bar 26 is to be pressed upwardly and 5 removed from the recesses 23.

While I have shown but two sets of oilers on the spring 10, it is to be understood that any number of such oilers may be applied to a spring. It is also to be noted that all 10 the pressures applied to the spring 10 by my improved oiler are yielding so that the normal operation of the spring 10 is not affected.

While I have shown one embodiment of 15 my invention, it is to be understood that it is for purposes of illustration only, for many changes may be made therein without departing from the spirit of my invention.

I claim:—

20 1. In a spring oiler, the combination with a leaf spring, of oiling members mounted on the sides thereof, each of said members comprising a reservoir for oil and means for distributing the oil to said spring and compres-

sible dust guards mounted in said members 25 to shield said means.

2. In a spring oiler, the combination with a leaf spring, a link bearing on the top of said spring, oiling members comprising means for oiling said spring each slidably 30 connected at one end to said link, a locking bar slidably connected to the other ends of said members and a spring for pressing said link and members towards said leaf spring.

3. In a spring oiler, the combination with a leaf spring, a link mounted on the top of said spring, inclines on said link, oiling members comprising means for oiling said spring, inclines at one end for resting on the inclines on said link and inclines at the other 40 end, a locking bar comprising inclines resting upon said last named inclines, and a spring for pressing corresponding inclines together, whereby said oiling members are yieldingly held upon said leaf spring. 45

In testimony whereof, I affix my signature.

EDWARD W. LEECH, JR.
